UNITED STATES PATENT OFFICE.

WILLIAM J. LUTTON, OF PATERSON, NEW JERSEY, ASSIGNOR OF ONE-HALF TO
MAURICE FRANCK, OF PATERSON, NEW JERSEY.

PATTERN MECHANISM FOR LOOMS.

Application filed August 28, 1923. Serial No. 659,760.

To all whom it may concern:

Be it known that I, WILLIAM J. LUTTON, a citizen of the United States, and resident of Paterson, in the county of Passaic and 5 State of New Jersey, have invented a new and useful Improvement in Pattern Mechanism for Looms, of which the following is a specification.

This invention relates to a pattern mechanism for looms and more particularly to a supplemental mechanism adapted to be combined with a shuttle box pattern chain mechanism and a multiplier pattern chain mechanism of well known construction and 10 operation, by means of which supplemental mechanism a different number of picks of filling may be inserted without interfering with the use of the ordinary box pattern chain and multiplier chain mechanisms in 15 the usual way.

This invention consists in certain novel features of construction and arrangement, whereby a pick and pick motion may be produced on a two weave pattern chain of 20 very few bars and thus materially reducing the cost of the pattern chain also the weight thereof.

A practical embodiment of my invention is represented in the accompanying drawings, in which

Fig. 1 represents a side elevation of a portion of a loom having my invention applied thereto.

Fig. 2 represents a detailed rear elevation, 35 on an enlarged scale, of my invention and the parts adjacent thereto.

Fig. 3 represents a vertical section taken inside the frame of the parts shown in Fig. 2, certain portions being broken away to 40 show other parts more clearly.

Fig. 4 represents a similar view of the parts in another position.

Fig. 5 represents a vertical section taken in the plane of the line V—V of Fig. 2, 45 looking in the direction of the arrows, and

Fig. 6 represents a vertical section taken in the plane of the line VI—VI of Fig. 2, looking in the direction of the arrows.

The frame of the loom is denoted by 1, 50 the reciprocating support for the drop boxes by 2, the lay by 3, the flexible connections by 4, which connections are arranged to connect the drop boxes and the connecting levers 5. The vibrator levers 6 are each 55 provided with a mutilated gear 7 loosely

mounted thereon, and an arm 8, which connects the gear with its connecting lever 5. The heddle operating pattern chain supporting wheels 9 are secured to rotate with a shaft 10, which is provided with a spur gear 60 11 in mesh with a pinion 12 carried by a shaft 13.

A mutilated cylinder gear 14 fast on the shaft 13 is arranged to coact with the mutilated gears 7. A similar mutilated cylinder gear 15 fixed on a shaft 16 also coacts with the gears 7. The mutilated cylinder gear 14 is driven from a vertical shaft 17 through mitre gears 18, 19, while the mutilated cylinder gear 15 receives its motion from the 70 vertical shaft 17 by means of mitre gears 20, 21.

The parts to which I have thus briefly alluded are well known in the art, combined and arranged substantially as shown, and it 75 is not thought necessary to give a detail statement of their operation, since the same is well known to those skilled in the art, my present invention pertaining to certain means for controlling the operation of the 80 above named parts in order to multiply the effect of a supplemental shuttle box pattern chain on the pattern chain, thereby saving length of chain.

The shuttle box pattern chain mechanism 85 comprises a cylinder 22 fast on a sleeve 23 mounted on the shaft 10. The cylinder 22 has mounted thereon a box pattern chain 24 made up of links and bars carrying mutilated rolls and tubes for the shuttle box 90 indicator levers in the usual manner.

Connected with the sleeve 23 is a star-wheel 25 which is operated by a pinwheel 26 splined on a shaft 27 driven from the shaft 13 by means of gears 28, 29. The 95 sleeve 30 having the multiplier pattern chain cylinder is mounted on the shaft 10 and carries a multiplier chain 31 which is composed of links and bars carrying rolls and tubes in the usual manner. The sleeve 30 also has a star-wheel 32 which is operated by a pinwheel 33 splined on the shaft 27. A longitudinally movable rod 34 is mounted in suitable bearings and carries a forked arm 35, which engages an annular recess in the hub 100 of the pinwheel 26, to move the pinwheel into and out of engagement with the star-wheel 25. A collar 36 is fixed on the longitudinally movable rod 34, which collar has a notch 37 arranged to receive the upper end 110

of a lever 38 pivoted at 39 on a stationary rod 40, which is supported in a lug 41 on the frame 1. The lever 38 is provided with an arm 42, which depends below the pivot 39 in position to receive one end of a helically coiled retraction spring 43. A second arm 44 projects from the lever 38 and is connected through a connector 45 with an indicator lever 46, pivotally supported at 47 and arranged to extend over the multiplier pattern chain 31. By reason of the rotary motion of the multiplier pattern chain a roller 48 or a tube 49 will pass under the indicator lever 46 and through the connector 45, move the lever 38 and with it the longitudinal moving rod 34, to carry the pinwheel 26 into and out of engagement with the star-wheel 25, thereby causing the rotation of the box pattern chain cylinder 22 and the box pattern chain 24 in the usual manner.

A second longitudinally movable rod 50, mounted in suitable bearings, has attached thereto a forked lever 51, which engages an annular recess in the hub of the pinwheel 33. A collar 52 is fixed on the longitudinally movable rod 50 and has a notch 53 arranged to receive the upper end of a lever 54 pivoted at 55, on the stationary rod 40. A downwardly extending arm 56 of the lever 54 has attached thereto one end of a helically coiled retraction spring 57, while the other end engages a lug 58 depending from a collar 59 fast on the rod 40. An arm 60 extends outwardly from the lever 54 in position to receive the lower end of a connector 61; the upper end of the connector 61 is bent to form an indicator lever 62, which extends over the box pattern chain 24 and is adapted to be engaged by a mutilated roll 64. The rotary movement of the box pattern chain 24, will through the engagement of the mutilated roll 64 with the lever 62, raise the lever and by reason of the movement of the connector 61 move the rod 50 to carry the pinwheel 33 into and out of engagement with the star-wheel 32, thereby causing the star-wheel to rotate and actuate the multiplier chain 31. The lowering of the indicator lever 62 will, through the connections of the pinwheel 33, move the pinwheel to disengage it from the star-wheel 32, and leave the star-wheel and the multiplier pattern chain 31 at rest.

Extending over the box pattern chain 24 is an indicator lever 65, one end of which is pivoted on a rod 66, which is also the fulcrum of the vibrating levers 6, and the other end turned downwardly in position to engage bars 67 of the box pattern chain 24, which project into the path of the indicator lever. This lever 65 is normally held at the limit of its downward movement by a link 68 which connects the lever with a bell crank lever 69, the arms 70 of which is arranged to receive the other end of the spring 43.

A supplemental shuttle box pattern chain 71, made up of links and bars carrying rolls, is mounted on a cylinder 72 fast on a shaft 73, which is journalled in the frame 1. One end of the shaft 73 has a gear 74 keyed thereon and arranged to mesh with the gear 11 fast on the shaft 10. A series of rocking levers 75 are arranged to extend over and be engaged by the rollers or bars of the supplemental box pattern chain 71. Each of the rocking levers 75 is provided at one end with an inverted U-shaped slot 76 which normally rests upon a rod 77 carried by the frame 1. This rod serves as the fulcrum upon which the rocking levers may oscillate. The rocking levers are held in position on the rod 77 by means of an oscillating arm 78 which is loosely mounted on a shaft 79 journalled in a bracket 80 carried by the frame 1. The other end of each of the rocking levers is connected to the vibrator levers 6 by a link 81, so that as the rocking levers are acted upon by the rolls or bars of the supplemental box pattern chain 71, the vibrating lever 6 will be moved accordingly, and the mutilated gears 7 brought into position to mesh with either of the mutilated cylinders gears 14, 15 and actuate the connecting levers 5 and hence, the drop box support for the shuttles (not shown).

The rocking levers 75 are intermittently rendered inoperative by means of the extended bars 67 of the box pattern chain 24, which bars engage and lift the lever 65 which in turn is connected to the oscillating arm 78 by a strap 82. When the oscillating arm 78 is raised, the rocking levers 75 will be free to move away from the rod 77 so that when the rolls on the supplemental chain act upon the rocking levers they will be lifted from their fulcrum on the rod 77, as clearly shown in Fig. 4. After the extended bar 67 has passed from beneath the lever 65 the spring 43 actuates the bell crank lever 69, link 68, strap 82 and exerts a pressure on the oscillating arm 78 which returns the U-shaped ends of the rocking levers 75 to the rod 77.

In operation:

Assuming the parts to be in the position shown in Figs. 1, 2, 3, 5 and 6, the supplemental pattern chain 71 is driven from the pinion 12 through the spur gear 11 on the shaft 10 and the gear 74 fast on the shaft 73. As the rolls on the supplemental chain are brought into position to act upon the rocking levers 75, the vibrators 6 through the links 81, which connect the levers 75 and vibrators 6, will actuate the respective shuttle box mechanism. In the revolution of the shuttle box pattern chain 24, the extended bars 67 will be moved into position to engage and lift the lever 65 which in turn will rock the oscillating arm 78 through the strap 82, which connects the lever 65 and

5 oscillating arm 78. When the oscillating arm 78 is raised, the rocking levers 75 are free to be lifted from the rod 77, to the position shown in Fig. 4, so that as the rolls 10 on the supplemental chain come into contact with the rocking levers 75, the slotted end of the levers 75, which was previously the fulcrum, will be raised and the upper end 15 of the links 81, which are connected to the levers 75 and vibrators, will form the pivots on which the rocking levers 75 swing.

In the passing of the extended bar 67 from the lever 65, the spring actuated bell crank lever 69, with its link 68, will cause the 15 lever 65, strap 82 and oscillating arm 78 to move downwardly to their normal positions.

The downward movement of the oscillating arm 78 will press upon the rocking levers 75 until the slots 76 in the end of the 20 levers 75 are again seated on the rod 77, whereupon the rolls on the supplemental chain 71 will rock the levers 75 on the rod 77, which in turn actuates the links 81, the vibrators 6 and their adjacent mechanisms.

25 From the foregoing it will be understood that, when the pinwheel 26 is in engagement with the star-wheel 25, as shown in Figs. 1, 2, 3, 5 and 6, the box pattern chain 24 will be rotated until the mutilated roll 64, 30 carried by the box pattern chain 24 comes under the lever 62. This roll 64 raises the lever 62, actuates the connector 61, which in turn moves the rod 50 and pinwheel 33 into engagement with the star-wheel 32 which 35 rotates the multiplier pattern chain 31. During the revolution of the multiplier pattern chain 31, the box pattern chain will remain stationary until the multiplier pattern chain 31 causes the next roll 48 to come under and actuate the indicator lever 46. The 40 movement of this indicator lever 46 will raise the connector 45, rock the lever 38 with its longitudinal rod 34 and pinwheel 26, which pinwheel 26 will move into engagement with the star-wheel 25, which again 45 actuates the cylinder 22 and box pattern chain 24. Thus it will be seen that while the box pattern chain 24 is at rest, the multiplier pattern chain 31 will continue in motion, 50 and when the box pattern chain 24 is brought into action the multiplier pattern chain 31 will remain idle.

The mechanism for controlling the operation of the supplemental box pattern chain 55 may be actuated in conjunction with the mutilated roll 64, by placing the extended bars 67 on the box pattern chain in cooperative relation with the mutilated roll 64, or in other words, the bars carrying the mutilated roll 64 may be lengthened to form the extended portions 67. Thus it will be seen that the box pattern chain will bring the extended bars 67 into contact with the lever 65, which will be lifted, and by reason of 60 the strap 82, raise the oscillating arm 78 to

the position shown in Fig. 4. When this oscillating arm 78 is raised, the rocking levers 75, which are connected to the vibrator 6, will be free to move away from the rod 77, so that the rolls on the supplemental 70 box pattern chain 71 will lift the rocking levers 75 at their fulcrums and thereby render the vibrators 6 and their respective shuttles inoperative. At this time, the shuttle box called in by the box pattern chain 75 24 will remain stationary in line with the raceway and the shuttle of that box operated until the multiplier pattern chain 31 again brings in a roll 48 to actuate the lever 46, which in turn through its adjacent mechanism will move the pinwheel 26 into engagement with the star-wheel 25 thereupon setting the box pattern chain 24 in motion and allowing the mechanism to rock the fulcrum of the levers 75 on the rod 77, and the 80 supplemental box pattern chain 71 to operate the shuttles as desired.

85 My invention shown and described sets forth a loom having a pick and pick motion on a two weave pattern chain and by reason 90 of the construction and arrangement of the supplemental shuttle box pattern chain with the adjacent mechanism, the chain may be automatically thrown into and out of operation, thereby controlling the pick and pick 95 part of the pattern. When thrown out of operation the work of filling the pattern is placed upon the shuttle box pattern chain, allowing a run of one or more shuttles in connection with the multiplier pattern chain 100 mechanism, as desired.

The advantages of my improvements will be readily perceived by those skilled in the art, and may be easily applied to box pattern chain and multiplier chain mechanisms 105 of ordinary and well known construction.

I desire it to be understood that various changes may be resorted to in the form, construction and arrangement of the several parts without departing from the spirit and 110 scope of my invention; hence, I do not intend to be limited to the details herein shown and described except as they may be included in the claims.

115 What I claim is:

1. In a pattern mechanism of a loom, the combination with a shuttle box pattern chain, a multiplier pattern chain, mechanism coacting with said chains to control the movement of the chains, and vibrating 120 levers, of a supplemental shuttle box pattern chain, rocking levers coacting therewith and connected to the vibrating levers, and means for rendering said rocking levers inoperable.

125 2. In a pattern mechanism of a loom, the combination with a shuttle box pattern chain, a multiplier pattern chain, mechanism coacting with said chains to control the movement of the chains, and vibrating 130

levers, of a supplemental shuttle box pattern chain, rocking levers coacting therewith and connected to the vibrating levers, and means actuated by the first named shuttle box pattern chain for rendering said rocking levers inoperable.

3. In a pattern mechanism of a loom, the combination with a shuttle box pattern chain, a multiplier pattern chain, mechanism coacting with said chains to control the movement of the chains, and vibrating levers, of a supplemental shuttle box pattern chain, rocking levers coacting therewith and connected to the vibrating levers, said 10 rocking levers being provided with a movable fulcrum, and means for controlling the position of the fulcrum of the rocking levers.

4. In a pattern mechanism of a loom, the combination with a shuttle box pattern chain, a multiplier pattern chain, mechanism coacting with said chains to control the movement of the chains, and vibrating levers, of a supplemental shuttle box pattern chain, rocking levers coacting there- 20 with and connected to the vibrating levers, said rocking levers being provided with a movable fulcrum, and means actuated by the first named shuttle box pattern chain for controlling the position of the fulcrum 30 of the rocking levers.

5. In a pattern mechanism of a loom, the combination with a shuttle box pattern chain, a multiplier pattern chain, mechanism coacting with said chains to control the movement of the chains, and vibrating levers, of a supplemental shuttle box pattern chain, rocking levers coacting therewith and connected to the vibrating levers, said 35 rocking levers being provided with a movable fulcrum, and an oscillating means for controlling the position of the fulcrum of the rocking levers.

6. In a pattern mechanism of a loom, the combination with a shuttle box pattern chain, a multiplier pattern chain, mechanism coacting with said chains to control the movement of the chains, and vibrating levers, of a supplemental shuttle box pattern chain, rocking levers coacting there- 45 with and connected to the vibrating levers, said rocking levers being provided with a movable fulcrum, and an oscillating means actuated by the first named shuttle box pattern chain for controlling the position of the fulcrum of the rocking levers.

7. In a pattern mechanism of a loom, the combination with a shuttle box pattern chain, a multiplier pattern chain, mechanism coacting with said chains to control the movement of the chains, and vibrating levers, of a supplemental shuttle box pattern chain, rocking levers coacting there- 55

with and connected to the vibrating levers, said rocking levers being provided with a movable fulcrum, an indicator lever actuated by the shuttle box pattern chain, an arm adapted to engage the rocking levers for controlling the position of the fulcrum of the rocking levers and a strap connecting said indicator lever and arm. 65

8. In a pattern mechanism of a loom, the combination with a shuttle box pattern chain, a multiplier pattern chain, mechanism coacting with said chains to control the movement of the chains, and vibrating levers, of a supplemental shuttle box pattern chain, rocking levers coacting therewith and connected to the vibrating levers, said rocking levers being provided with a movable fulcrum, an oscillating indicator 70 lever actuated by the shuttle box pattern chain, an arm adapted to engage the rocking levers for controlling the position of the fulcrum of the rocking levers, and a strap connecting said indicator lever and arm. 75

9. In a pattern mechanism of a loom, the combination with a shuttle box pattern chain, a multiplier pattern chain, mechanism coacting with said chains to control the movement of the chains, and vibrating levers, of a supplemental shuttle box pattern chain, rocking levers coacting therewith and connected to the vibrating levers, said rocking levers being provided with a movable fulcrum, an oscillating indicator 80 lever actuated by the shuttle box pattern chain, an arm adapted to engage the rocking levers for controlling the position of the fulcrum of the rocking levers, and a strap connecting said indicator lever and arm. 85

10. In a pattern mechanism of a loom, the combination with a shuttle box pattern chain, a multiplier pattern chain, mechanism coacting with said chains to control

the movement of the chains, and vibrating levers, of a supplemental shuttle box pattern chain, rocking levers coacting therewith and connected to the vibrating levers, said rocking levers being provided with a slot, a pivot on the frame arranged to coact with said slot, an oscillating indicator lever actuated by the shuttle box pattern chain, an oscillating arm adapted to engage the rocking levers for controlling the position of the slot on the pivot, and a strap connecting said indicator lever and arm. 100

11. In testimony, that I claim the foregoing as my invention, I have signed my name this 21st day of August, A. D. 1923. 110

WILLIAM J. LUTTON.
